US00D843938S

(12) **United States Design Patent** (10) Patent No.: **US D843,938 S**
(45) Date of Patent: **** Mar. 26, 2019**

(54) **WIRELESS EARSET CASE**

- (71) Applicant: **LG ELECTRONICS INC.**, Seoul (KR)
- (72) Inventors: **Soonhyun Park**, Seoul (KR); **Dongsoon Kim**, Seoul (KR); **Hyunchul Kim**, Seoul (KR); **Sunmin Lee**, Seoul (KR)
- (73) Assignee: **LG ELECTRONICS INC.**, Seoul (KR)
- (**) Term: **15 Years**
- (21) Appl. No.: **35/503,381**
- (22) Filed: **Jan. 20, 2017**
- (80) **Hague Agreement Data**

Int. Filing Date: **Jan. 20, 2017**Int. Reg. No.: **DM/095245**Int. Reg. Date: **Jan. 20, 2017**Int. Reg. Pub. Date: **Jul. 21, 2017**(30) **Foreign Application Priority Data**

(57) **CLAIM**

The ornamental design for a wireless earset case, as shown and described.

DESCRIPTION

1. Wireless earset case
  - 1.1 : Perspective
  - 1.2 : Front
  - 1.3 : Back
  - 1.4 : Left
  - 1.5 : Right
  - 1.6 : Top
  - 1.7 : Bottom
  - 1.8 : Reference, showing the wireless earset case in an open position in an environment of use
- The broken lines shown in figure 1.8 depict portions of the wireless earset case and environment that form no part of the claimed design.

1 Claim, 7 Drawing Sheets(56)
